THREE-WAY FOUNDATION GARMENT

George G. Wanish, Cortland, N. Y.

Application November 29, 1950, Serial No. 198,150

2 Claims. (Cl. 2-30)

1

This invention relates to new and useful improvements in foundation garments; and, more particularly, the aim is to provide a novel and valuable foundation garment which is a three-ways such garment because it will serve three purposes.

According to the present invention, the combination is provided of a corselet and a girdle, with the latter constituting a definitely positioned yet completely detachable inner belt in the corselet, whereby with the corselet and the girdle both worn the foundation garment is an inner-belt corselet, whereby with the inner belt detached and removed from the corselet the latter is worn as an ordinary corset, and whereby with the inner belt detached and removed from the corselet said inner belt is worn as a girdle. It is consequently clear that the three ways the new garment can be used will afford the equivalent of three separate garments each for serving its own distinctive purpose.

Said girdle, to act as just explained as an inner belt when worn with the corselet, is so constituted that it functions to give all the flesh-mass shiftings and figure controlling results of the usual girdle. The outer garment unit, which is the corselet, is so constituted that when worn without the inner belt it is a comfortable unbelted corselet having all the important features and figure controlling utilities of a corselet of this type. In the case of a figure needing that support and control to be afforded not otherwise than by a full corset worn over a girdle as a primary or first applied waist and hips constrictor, the corselet of the present invention, and also the girdle, this last as an inner belt member attached to the corselet, will both be worn.

A feature of the invention, further, is a coupling means for the corselet and girdle, which is in the nature of a pocket at the inside of the back portion of the corselet, and which insures most efficient use of the girdle when it and also the corselet is worn, but which permits instantaneous complete detachment of the girdle from the corselet when desired.

The corselet is herein illustrated as having the usual side elastic panels, and as provided, also preferably, with a hook and eye closure for a side opening; but, as will be understood, modifications are possible within the invention.

Also exemplifyingly, the inner belt or girdle is herein illustrated as preferably provided with a hook and eye closure, as having said closure offset from the central front portion of the girdle, as having a lacing extending in an up and down direction at said front portion, and, further, as having elastic side sections. However, aside from other variations within the invention, it is con-

2

templated that said lacing feature may be eliminated, as it is not entirely necessary because of said elastic side sections, which will permit the girdle, when used solely as such, or when used as an attached inner belt of the corselet, to expand considerably.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

15 Fig. 1 is a view in front elevation showing a now favored embodiment of the invention, with a side closure for the corselet partly open near the bottom of the garment.

Fig. 2 shows said garment in top plan.

Fig. 3 is a view similar to Fig. 2, but with the sides and front portions of the corselet merely indicated in dot and dash lines, thereby to show more clearly the front portions of the inner belt or girdle.

25 Fig. 4 is a front view of said girdle, as disposed forwardly of the rear portion of the corselet fragmentarily shown; this view being as though taken on the line 4-4 of Fig. 3.

Fig. 5 is an inside view looking toward said 30 rear portion of the corselet, with the inner belt or girdle removed, for more clearly showing the aforesaid means in the nature of a pocket.

Referring now to the drawings in more detail, 35 10 designates the corselet, the same shown as having a pair of elastic side panels 11, and above these a brassière portion 12 including a pair of shoulder straps 14. These latter are illustrated as incorporating tape-like parts which are longitudinally elastically stretchable. In various 40 other respects the corselet 10 is shown as more or less conventionally constructed and equipped; for example, there are included substantially triangular elastic gores, one shown at 15 as at the top rear of the corselet and the other shown at 16 as at the bottom front of the corselet, and a front lateral stiffener is indicated at 17 and two rear vertical stiffeners at 18, 19.

45 The corselet 10 is further shown as being of the side opening type, such opening designated 19, and shown as having its closing means comprised of a suitable number of eyes 20 and complementary hooks 21.

To provide the aforesaid means in the nature 50 of a pocket, a special vertically disposed inner section 22 is included; this, to provide said pocket as a tunnel 23 of a definite height and at a particular location in the corselet 10, being across its upper end attached to the back panel 24 of

the corselet by way of a top cross tape 25 suitably stitched to said back panel and across its lower end attached to said back panel by way of a bottom cross tape 26 suitably stitched to said back panel. As said section 22 also is shown, the same is braced along both its long vertical edges by stiffeners 27.

The inner belt or girdle unit is as a whole designated 28, and the just-mentioned definite height of the tunnel 23 should be such as properly to receive the rear portion of the girdle 28 and thereby to predetermine that the girdle will be held substantially to a definite disposition within the corselet 10 and relative to the over-all height of the latter as indicated in Fig. 4.

The girdle 28 is shown as having, toward its front but at points laterally offset from the central portion of its front, elastic sections 29. Also, the girdle 28 is shown as having an opening 30 laterally offset from said central portion of the girdle's front, with one side of said opening contributed by a marginal portion of one of the elastic sections 29; while the closing means for the opening 30 is indicated in Fig. 4 as comprised of a line of hooks and eyes similar to those described in connection with the side opening 19 of the corselet 10.

The front portion of the girdle, between the two elastic sections 29, is further shown as comprising two inelastic sections 31, 31, each having a stiffener 32; these sections 31 being equipped along their adjacent margins with lines of eyelets having threaded therethrough a lacing 33 whereby said margins may be pulled up closer and closer together as said lacing is tightened up more and more. Desirably included, too, is a fabric member 34 for acting as a flexible connector between the two sections 31 and as a shield to cushion any part of the lacing 33 against cutting onto the flesh at the abdominal wall.

As in ordinary foundation garments, the new garment of the present invention is desirably equipped with a suitable plurality of garters for being engaged with the stockings worn. As herein shown, the arrangement provided is characterized by the inclusion of a pair of front garters 35 and a pair of rear garters 36 suspended from the corselet 10, and a pair of side garters 37 suspended from the girdle 28.

In wearing the girdle 28 alone, the same, after being slid out of the pocket or tunnel 23, is placed around the waist of the wearer, and then closed at the opening 30; provided the same person has worn the girdle before, with the consequence now that the lacing 33 is properly tightened. Otherwise, after the opening 30 is closed, the lacing 33 is tightened and tied.

In wearing the corselet 10 alone, as an ordinary corset with inbuilt brassière, the same is donned as in any ordinary side opening corset; following detachment of the girdle 28.

In wearing the new foundation garment in its entirety, that is, with the girdle 28 at its central back portion pocketed in the tunnel 23 and so now ready to act in its capacity as an inner belt, the garment is placed around the body, and with the wearer's shoulders under the straps 14, first the girdle is secured around the waist as described in the paragraph second preceding, and then the corselet 10 is adjusted, and, as usual in the case of a side opening corset, closed at its opening 19.

While I have illustrated and described the preferred embodiment of my invention, it is to be understood that I do not limit myself to the

precise construction herein disclosed and the right is reserved to all changes and modifications coming within the scope of the invention as defined in the appended claims.

Having thus described my invention, what I claim as new, and desire to secure by United States Letters Patent is:

1. A combination foundation garment of the type described, comprising an outer corselet having an elongated rectangular-shaped rear panel and a closable side opening, an inner belt of a vertical height less than said corselet positioned within said corselet and having a closable side opening, and a vertically elongated inner section substantially similar in shape to the rear panel and positioned against the inner face and extending the width of the rear panel of said outer corselet, said inner section being secured along its top and bottom edges to the top and bottom edges of the inner face of said rear panel and being free of said rear panel along its vertical side edges forming a closed tunnel with open ends between the adjacent faces of said rear panel and said inner section, said inner belt having its intermediate portion extended slidably through said tunnel formed by the inner section and rear panel, to be worn as a girdle independently of said corselet, said inner section being of a length slightly greater than the vertical height of said inner belt and secured to said rear panel closely adjacent the top and bottom edges of said inner belt to hold said inner belt to a definite disposition within said corselet.

2. A combination foundation garment of the type described, comprising an outer corselet having an elongated rectangular-shaped rear panel and a closable side opening, an inner belt of a vertical height less than said corselet positioned within said corselet and having a closable side opening, and a vertically elongated inner section substantially similar in shape to the rear panel and positioned against the inner face and extending the width of the rear panel of said outer corselet, said inner section being secured along its top and bottom edges to the top and bottom edges of the inner face of said rear panel and free of said rear panel along its vertical side edges forming a closed tunnel with open ends between the adjacent faces of said rear panel and said inner section, said inner belt having its intermediate portion extended slidably through said tunnel formed by the inner section and rear panel, to be worn as a girdle independently of said corselet, said inner section being of a length slightly greater than the vertical height of said inner belt and secured to said rear panel closely adjacent the top and bottom edges of said inner belt to hold said inner belt to a definite disposition within said corselet, and stiffeners mounted along the outer vertical side edges of said inner section.
